UNITED STATES PATENT OFFICE.

JOHN B. AUFULDISH, OF DAYTON, OHIO.

STARTER FOR EXPLOSIVE-ENGINES.

1,143,930.

Specification of Letters Patent. Patented June 22, 1915.

Application filed December 1, 1911. Serial No. 582,208.

To all whom it may concern:

Be it known that I, JOHN B. AUFULDISH, a citizen of the United States, residing at Dayton, in the county of Montgomery and State of Ohio, have invented certain new and useful Improvements in Starters for Explosive-Engines, of which the following is a specification, reference being had thereto in the accompanying drawing.

13 This invention relates to starters for explosive engines and more particularly to starters of this character which employ acetylene gas as the actuating medium.

The object of the invention is to produce a 18 starter which can be operated by acetylene gas at a pressure so low that it will be absolutely safe.

To accomplish this result it is a further object of the invention to provide a distributing device having a storage chamber or pocket close to the engine from which the gas can pass quickly and with a minimum of friction to the cylinder in which it is to be exploded; to provide one of these chambers or pockets for each cylinder of the engine; and to provide means for successively connecting each pocket with its cylinder.

It is also an object of the invention to provide means whereby the charge to be introduced into the cylinder may be measured and all danger of introducing too large a charge thus eliminated.

It is a further object of the invention to provide a device of this character which will be simple and durable in its construction, of light weight and inexpensive to manufacture.

In the accompanying drawings, Figure 1 is a top, plan view of an engine showing my invention applied thereto; Fig. 2 is a longitudinal sectional view, taken centrally through the distributing device; Fig. 3 is a transverse section taken on the line *a a* of Fig. 2 and looking in the direction of the arrows; Fig. 4 is a transverse section taken on the line *v v* of Fig. 2 and looking in the direction of the arrows; Fig. 5 is a detail of one of the valves; Fig. 6 is a view of a portion of a gas tank showing the pipes leading therefrom to the starter and to the lights; Fig. 7 is a vertical section through one of the plugs by means of which the gas may be introduced into the engine; Fig. 8 is a top, plan view of the same; Fig. 9 is a 55 detail of the mechanism for imparting

movement to the shaft to throw the same off dead center; Fig. 10 is a longitudinal sectional view of the distributing device showing a slight modification thereof; Fig. 11 is a longitudinal section of a further modified distributing device; and Fig. 12 is a transverse section taken on the line *a a* of Fig. 11.

In these drawings I have illustrated my invention as applied to an explosive engine of the type ordinarily employed on automobiles and this engine is indicated by the reference numeral 1 in Fig. 1 and comprises four cylinders. To start this engine without first turning it over by hand I introduce into one or more of the cylinders thereof a quantity of explosive gas and explode this gas, thereby imparting movement to the piston of the particular cylinder in which the gas is exploded. The movement of this piston, of course, actuates the shaft and other pistons, thus causing charges of gas to be drawn into the other cylinders and exploded in the usual manner.

The particular device here illustrated is designed for use in connection with acetylene gas which, in the present instance, is secured from a gas container of the type commonly known as the "Frosto-Lite" tank 2, which may be carried upon an automobile in any suitable position. It will be understood, however, that any suitable explosive gas may be employed and that this gas, whatever its character, may be obtained from any suitable source of supply.

The distance between the tank or other source of supply and the cylinders of the engine is very material and the passage of the gas through the conduit leading from the tank to the cylinder is very slow, there being a large amount of friction between the gas and the walls of the conduit. As a result where there is a direct connection between the tank and the cylinder in order to inject a charge into the cylinder, it is necessary to utilize a comparatively high pressure, in many instances as high as fifteen pounds. The highly explosive quality of acetylene gas renders this pressure dangerous, yet without the high pressure the gas cannot be properly introduced into the cylinder. To overcome these difficulties and introduce the gas into the cylinders quickly and with a minimum of friction at a low pressure by interposing between the tank and the cylinders a distributing device con-

taining a plurality of chambers or pockets adapted to receive and store small, and preferably measured, quantities of gas. These pockets are connected with the respective 5 cylinders by conduits, each of which is controlled by mechanism arranged within reach of the chauffeur. The conduit leading from the tank to the distributing device is preferably provided with a regulating valve and 10 gage, as shown at 3. By setting this valve to maintain the pressure in the conduit at a low degree, say one and one-half pounds, it becomes impossible to secure a high pressure either in the distributing device or the engine cylinders. The gas under low pressure 15 moves through the conduit and fills the several pockets of the distributing device. The conduit may then be closed between the distributing device and the tank or it may be left open. When it is desired to start the engine the conduits leading from the pockets to the respective cylinders are opened and the gas which is confined in the pockets under low pressure and is of a highly expansive 20 character, will quickly enter the cylinders, in which it may be ignited. Of course, it is only necessary to explode a charge in one cylinder to start the engine but all the pistons in all the cylinders are not in a condition 25 to permit the cylinder to receive and explode the charge and to avoid the necessity of determining the position of the pistons in the several cylinders I prefer to introduce a charge of gas into each cylinder. Then 30 the charge in the cylinder which is in the proper condition for starting will be exploded when the circuit is completed.

It will be obvious that this distributing device may take various forms but for the 40 purpose of illustration I have here shown the same as comprising a cylindrical housing 4 supported in a suitable position upon the automobile. Preferably the housing or distributor is supported from the dash 5 and 45 to this end it is provided at its rear end with a plate 6 adapted to be secured to the dash and having a forwardly projecting screw-threaded flange 7 adapted to be screwed into the rear portion of the housing. Thus when 50 the plate 6 is screwed or otherwise secured to the dash the distributor as a whole will be supported therefrom.

The forward portion of the housing, that is, the portion farthest removed from the 55 dash, has formed therein a series of pockets or chambers 8, there being one of these chambers for each cylinder of the engine, in the present instance, four. These pockets may be formed by boring or otherwise cor- 60 ing out the housing or body portion of the distributor and in such instances the bottoms of the pockets will be formed integral with the side walls of the housing, as shown in Fig. 2. The pockets preferably terminate 65 short of the forward end of the housing and

that portion of the interior of the housing lying between the forward end of the pocket and the forward end of the housing itself constitutes a chamber 9.

The forward end of each pocket may be closed by any suitable means, such, for example, as a screw-threaded disk or plug 10 inserted in the forward end thereof and having an aperture 11. These disks may also be provided with recesses 12 which, together with the apertures 11, enable the disk to be gripped and rotated by means of spanners. 70

The forward portion of the housing is closed by means of a screw-threaded cap or disk 13 which is screwed into the end of the housing and is spaced such a distance from the forward ends of the pockets as to form an inclosed chamber, as indicated at 9. The cap or closure 13 has an inlet opening 14 to which is connected a conduit 15 leading to the Presto-lite tank 2. 80

Where it is desired to utilize acetylene gas both for lighting and starting purposes the discharge apparatus of the tank, which is indicated as a whole at 16, may be provided with a T, 17, to one side of which is connected the conduit 15 leading to the distributor and to the other of which is connected the conduit 18 leading to the lamps. The regulating valve and indicator 3, which are interposed in the conduit 15 between the tank and the distributor, may be of any suitable character by means of which the amount of pressure in the conduit beyond the valve may be regulated. 90

The gas passes from the tank through the conduit 15 into the chamber 9 and thence through the apertures 11 into the several pockets. These apertures being normally open, and in the form shown in Fig. 2 always open, the gas has ample time in which to travel from the tank to the pockets and establish the desired pressure in the pockets, this action taking place when the starter is not in use. Each pocket is further connected by means of a suitable conduit with one of the cylinders of the engine. In the present instance these conduits are formed in the rear portion of the housing 4, as indicated at 19, and communicate at their outer ends with nipples 20 screwed into the exterior wall of the housing and connected by pipes 21 with the respective cylinders. 100

Suitable cut-offs are interposed between the pockets and their cylinders in order that the flow of gas from the pockets to the cylinders may be controlled. These cut-offs, as here shown, are in the form of rotary plug valves 22 having transverse ports 23 arranged at acute angles to the length of the valves and adapted to register, when the valves are in given positions, with the respective conduits on both sides of the valves, thus establishing communication between the respective pockets and their cyl- 110

inders. It will be apparent that each conduit 19 formed in the body of the distributor and the corresponding pipe 21 which communicates therewith constitutes in effect a single conduit leading from the respective pocket to its cylinder. The pockets in the valves are so arranged that they will be successively moved into registration with the respective conduits, thus establishing communication between the several pockets and their cylinders, in a prescribed order. The valves are rotated in unison in order to effect the establishment of communication between the pockets and their cylinders. In the present instance the rear end of the housing is provided with a space between that portion thereof in which the valves are mounted and the plate 6, as indicated at 24. Each valve has secured to its rear end and arranged within the space 24 a pinion 25. These pinions all mesh with a central pinion 26 rigidly secured to a shaft 27 journaled in the rear end of the housing, extending through the dash 5 and provided on its rear end with a handle 28. The rotation of this handle causes the valves to be rotated in unison and the gas to be admitted from the pockets to the cylinders in the order of firing. The handle has a spring-pressed pin 29 mounted therein and adapted to engage a recess 30 in the dash to hold the handle in its neutral position with all the valves in their closed positions. If desired, each valve 22 may also be provided with an exhaust port 31 adapted to register with an exhaust passage 32 in the outer wall of the housing and with that portion of the conduit 19 leading to the cylinder, when the port 23 is out of alinement therewith. In the present instance and for convenience of manufacture the housing is shown as formed in two parts, the line of division extending between the part having the pockets and the part in which the valves are mounted and the two parts being connected by screwing one into the other, as indicated at 33.

The several conduits or pipes 21 are connected with their respective cylinders by means of plugs 34 screw-threaded into the cylinder heads, as shown in detail in Fig. 8. Each of these plugs is provided with a needle valve 35 having a stem 36 extending above the plug and provided with a head 37 having a series of teeth 38 which may be engaged by a resilient finger 39 to hold the valve in adjusted positions. If desired, the top of the head 37 may have thereon marks or numbers to indicate the position of the valve. By making the inlet to the cylinders adjustable the inlet to the cylinder farthest removed from the distributor may be opened to a greater degree than the inlets to the cylinders nearer the distributor, thus permitting the gas to pass

more rapidly through the longer pipes and causing substantially equal quantities of gas to enter the several cylinders during a prescribed interval. If desired check valves 34^a may be interposed in the conduits to prevent the escape of gases from the engine through the conduits.

As above stated the pockets 8 are normally in communication with the tank and therefore normally contain charges of gas. When it is desired to start the engine the handle 28 is revolved through a complete revolution, thus connecting each pocket for a brief interval with its cylinder. During this interval gas will pass from the pocket to the cylinder. By then closing the ignition circuit, by means of the usual switch 40, the spark will be produced in that cylinder in which the piston is in the proper position and the gas thus exploded, thereby imparting movement to the piston and starting the engine.

It will be apparent in the construction above described that during the brief interval that the pockets are connected with their respective cylinders they are also connected with the tank. The interval is so short, however, that no considerable amount of gas will travel through the long conduit leading from the tank to the distributor and very little gas in excess of what is in the pockets will enter the cylinders. However, if it is desired to introduce a measured charge into each cylinder this can be done by interrupting communication between the pockets and the tank while the pockets are in communication with their cylinders.

In Fig. 10, I have illustrated one method of accomplishing this result. In this figure the construction is the same as that above described with the exception that the shaft which actuates the valves, and is here indicated at 41, extends through the distributor and terminates in the chamber 9 at the forward end thereof. Rigidly secured to the forward end of this shaft is a disk 42 having therein four apertures adapted, when the handle is in its neutral position, to register with the four apertures 11 connecting the chamber 9 with the respective pockets 8. When the handle has been moved out of its normal position and is in a position in which any one of the pockets may be connected with the cylinder the disk will be in a position to close the aperture 11 leading to that pocket, thereby interrupting the communication between the pocket and the tank.

In Figs. 11 and 12 I have shown another form of distributor which comprises but a single valve. In this type of distributor the body portion or housing 43 has a series of pockets 44 arranged parallel one with the other, the series extending lengthwise of the housing. Each pocket is connected by means of a port 45 with a passage or conduit 46

which, in turn, communicates with a supply pipe 47 leading from the source of supply. If desired this supply may be controlled by means of a valve 48 which is here shown as 5 a turn-plug valve interposed between the pipe and the passage. Each pocket communicates by means of a port 49 with a valve chamber 50 in which is rotatably mounted an elongated tapered plug valve 51 10 having ports to connect the several pockets successively with the conduits 52 leading to the cylinders. The valves may be rotated by means of a handle 53 mounted at its outer end on a valve stem 54. A pinion 55 is 15 secured to the opposite end of the valve and is connected by a pinion 56 with a pinion 57 on the valve 51. It will be noted that the turn plug valve and casing as here shown are provided with other ports. These additional 20 ports are not for use with acetylene gas but with other fluids and they need not be here described. It will be apparent that the operation of this distributor is substantially the same as that of the distributors 25 above described and that by means of it measured charges of gas can be introduced into the several cylinders.

It sometimes happens that the engine will stop on a dead center. When this takes 30 place it is necessary to move the shaft far enough to throw the engine off dead center before it is fired. In order that this may be done without the necessity of leaving the vehicle I secure to the fly wheel 58 a series 35 of projections 59 and pivotally mount on the frame of the machine a lever or pawl 60 arranged in a position to engage one of the projections 59. A plunger 61 is pivotally connected to the pawl 60 and extends 40 through the foot-board 62 of the machine where it may be actuated by the driver to impart the necessary movement to the shaft. A spring 63 coiled about the shaft within a 45 housing 64 tends to hold the pawl normally in its uppermost position and out of the path of the projections 59.

It will be apparent, therefore, that I have provided mechanism whereby acetylene gas or other gases of highly explosive character 50 may be utilized for starting an explosive engine with complete safety, the gas being admitted to the cylinders in quantities which are either measured or so controlled that a small amount of gas only can enter the cylinder and that this gas can be introduced into the cylinders and utilized at a low pressure; and further, that I have provided such a mechanism which is simple and inexpensive in its construction and which will not 55 be easily broken or disarranged.

While I have shown and described certain 60 embodiments of my invention it will be understood that these are chosen for the purpose of illustration only and that I do not 65 desire to be limited to the details of con-

struction shown and described, for obvious modifications will occur to a person skilled in the art.

Having thus fully described my invention, what I claim as new and desire to secure by Letters Patent, is:—

1. The combination, with an engine having a plurality of cylinders, of a casing having a plurality of chambers adapted to communicate with a source of gas supply, and operable means to connect said chambers with the respective cylinders of said engine.

2. The combination, with an engine having a plurality of cylinders, of a starter comprising a series of pockets adapted to receive and store quantities of gas, means to connect said pockets with the respective cylinders of said engine, and a single operating device to actuate the connecting means of all of said pockets.

3. The combination, with an engine having a plurality of cylinders, and a storage device to receive and store a quantity of gas under pressure, of means to connect said device with the cylinders of said engine and to cause measured portions of said gas to enter the respective cylinders.

4. The combination, with an explosive engine having a plurality of cylinders, and a source of gas supply, of a distributor, having a series of pockets, a connection between said pockets and said source of supply, other connections between said pockets and the respective cylinders of said engine, and means to open and close both the first-mentioned and the last-mentioned connections.

5. The combination, with an explosive engine having a plurality of cylinders and a source of gas supply, of a device having a plurality of storage chambers each connected with said source of gas supply and adapted to receive and store a charge of gas, connections between said chambers and the respective cylinders of said engine, operable means to control the last-mentioned connections, and a single device to actuate the controlling means for all of said last mentioned connections.

6. The combination, with an explosive engine having a plurality of cylinders, and a source of gas supply, of a device having a plurality of chambers each connected with said source of gas supply, and adapted to receive and store a quantity of gas, and means to successively connect said chambers with the respective cylinders of said engine.

7. The combination, with an engine having a plurality of cylinders, and a source of gas supply, of a combined storage and distributing device interposed between said source of supply and said engine, means to interrupt the communication between said device and said source of supply and to connect said device with the cylinders of said engine, whereby said device will receive and

store a supply of gas and distribute it among the cylinders of said engine.

8. The combination, with an engine having a plurality of cylinders, and a source of

5 gas supply, of a distributing device interposed between said source of supply and said engine and having a plurality of pockets, said pockets being normally in open communication with said source of gas supply, said pockets being normally disconnected from the cylinders of said engine, and means for establishing communication between said pockets and the respective cylinders of said engine.

15 9. The combination, with an explosive engine comprising a plurality of cylinders, and a source of gas supply, of a housing containing a plurality of storage chambers, a conduit leading from said source of gas supply to said housing and communicating with each of said chambers, a conduit leading from each chamber to the respective cylinder of said engine, and valves to control each of the last-mentioned conduits.

25 10. The combination, with an explosive engine comprising a plurality of cylinders, and a source of gas supply, of a housing containing a plurality of chambers, a conduit leading from said source of gas supply to said housing and communicating with each of said chambers, a conduit leading from each chamber to the respective cylinder of said engine, valves to control each of the last-mentioned conduits, an operating 30 handle, and a geared connection between said handle and each of said valves.

11. The combination, with an explosive engine comprising a plurality of cylinders, and a source of gas supply, of a housing containing a plurality of chambers, a connection 40 between each of said chambers and said source of supply, a connection between each chamber and the respective cylinder of said engine, an exhaust passage, and a valve to 45 interrupt the connection between said cylinder and the respective chamber and to connect said cylinder with said exhaust passage.

12. The combination, with an explosive engine, having a plurality of cylinders, and a source of gas supply, of a distributor having a plurality of chambers, a connection between said chambers and said source of supply, and an adjustable connection between each of said chambers and the respective cylinder of said engine, and means for interrupting said connection.

13. A starter for an explosive engine comprising a housing having at one end a plurality of pockets and a chamber, said chamber being in open communication with a suitable source of gas supply, and means for establishing communication between said chamber and the respective ports, conduits leading from the respective ports through said housing and adapted to be connected

with the cylinders of an engine, rotary valves mounted in said housing and arranged to control the respective conduits, and means for actuating said valves.

14. The combination, with an explosive 70 engine having a plurality of cylinders, and a source of gas supply, of a distributor having a series of pockets, a connection between said pockets and said source of supply, means for controlling said connection, other connections between said pockets and the respective cylinders of said engine, and means for controlling said last-mentioned connection.

15. The combination, with an explosive 80 engine having a plurality of cylinders, and a source of gas supply, of a distributor having a series of pockets, a connection between said pockets and said source of supply, means for controlling said connection, other connections between said pockets and the respective 85 cylinders of said engine, and a single means for controlling both the first-mentioned and the last-mentioned connections.

16. The combination, with an engine having a plurality of cylinders, and a supply of combustible fluid under pressure, of mechanism communicating with said supply of fluid to receive therefrom and to measure charges of combustible fluid under pressure and to distribute said charges to the respective cylinders of said engine.

17. The combination, with an engine having a plurality of cylinders, and a supply of combustible fluid under pressure, of mechanism communicating with said supply of fluid to receive therefrom and to measure charges of combustible fluid under pressure and to distribute said charges successively to the respective cylinders of said engine.

18. The combination, with an engine having a plurality of cylinders, and a supply of combustible fluid under pressure, of mechanism communicating with said supply of fluid to receive therefrom and to measure charges of combustible fluid under pressure and to distribute said charges to the respective cylinders of said engine, and operable 110 means to control said mechanism.

19. The combination, with an engine having a cylinder, a casing having a chamber 115 adapted to communicate with a source of gas supply, a rotatable device to connect said chamber with and disconnect the same from the cylinder of said engine, and means for simultaneously imparting rotation to said 120 rotatable device and for interrupting the communication between said chamber and said source of gas supply.

20. In a starter, a casing having a storage chamber adapted to communicate with a 125 source of gas supply, an operable device to control said communication, a second operable device to connect said chamber with the engine, both of said operable devices being supported externally of said chamber, and a 130

single operating member for both of said devices.

21. The combination with a multiple cylinder internal combustion engine, of a device 5 movable to successive positions to measure charges of combustible fluid and distribute the same to the several cylinders of said engine.

22. The combination with a multiple cylinder internal combustion engine, of means 10 for distributing measured charges of compressed combustible fluid successively to all of the cylinders of said engine.

23. The combination, with an engine having 15 a plurality of cylinders, and a source of gas supply, of a storage device to receive and

store a quantity of gas, means to connect said device with the cylinders of said engine, and means to cause substantially equal portions of said gas to enter the respective cylinders. 20

24. The combination, with an engine having a plurality of cylinders, of a distributor constructed and arranged to receive combustible fluid under pressure and to introduce measured charges of said fluid into the 25 several cylinders of said engine.

In testimony whereof, I affix my signature in presence of two witnesses.

JOHN B. AUFULDISH.
